PANEL CONSTRUCTION

Longueville H. Price, Sr., Atherton, and Henry Anthony Scarlett, San Francisco, Calif., assignors to Price Building Specialties Co., San Francisco, Calif., a firm

Application August 2, 1948, Serial No. 42,034

2 Claims. (Cl. 189—34)

1

This invention relates to an improved door and panel construction.

The principal object of this invention is to provide a metal panel construction particularly adapted for use in the construction of partitioning doors and panels, such as are commonly found in public lavatories and like places.

Another object of this invention is to provide a metal panel unit having a substantial thickness which comprises a pair of telescopically cooperating pans which when assembled together are held in operative relationship with one another by novel locking means.

Another object of this invention is to provide an improved metal panel construction which is characterized by a high degree of heat and sound insulating properties.

Another object of this invention is to provide a panel construction having a substantial thickness which requires no screws or bolts in its assembly.

A further object of this invention is to provide an improved metal panel construction having insulating properties, which is simple to assemble and install, and which is of sturdy and rugged construction.

Other objects of this invention will become apparent upon reading the following specification and referring to the accompanying drawings in which similar characters of reference represent corresponding parts in each of the several views.

In the drawings:

Fig. 1 is a perspective view of an assembled panel unit showing parts thereof broken away in section.

Fig. 2 is an exploded view of a panel unit showing its manner of assembly.

Fig. 3 is a sectional view taken on either line 3a—3a and/or line 3b—3b of Fig. 1.

Fig. 4 is a perspective view of a panel unit disposed between two vertical studs and showing parts of the panel unit broken away in section.

Fig. 5 is a sectional view taken on line 5—5 of Fig. 4.

Fig. 6 is a fragmentary sectional view of an end-corner of an assembled panel unit.

Referring now more specifically to the drawings, an assembled panel unit comprises a first pan, indicated generally at A, formed preferably of resilient metal, such as sheet steel, and a second pan formed similarly to pan A and indicated generally at B, and preferably, a sheet of suitable sound and heat insulating material disposed between pan A and B, indicated generally at C. The pans are preferably die stamped.

Referring particularly to Figs. 1, 2 and 3 pan

2

A may be formed from a flat rectangular piece of sheet metal or other suitable resilient material, provided with diagonal slits 7 at its four corners to enable the marginal edges of the rectangular piece to be bent outwardly at substantially right angles to the plane of the flat section 9 to form marginal flanges 8. Pan B is formed similarly to pan A and comprises a flat section 11 with marginal flanges 12 extending outwardly therefrom and lying in a plane substantially normal to the plane of flat section 11.

Marginal flanges 8 of pan A and marginal flanges 12 of pan B are curvilinear in cross-section, and the edges of flanges 8 are folded outwardly and doubled back along flanges 8 to form outer locking strips 13 having abutment edges 14. The edges of flanges 12 of pan B are folded inwardly and doubled back along the inner sides of flanges 12 to form inner locking strips 15, having abutment edges 16.

The outside outer margins of pan A, as defined by flanges 8, are slightly smaller than the inner margins of pan B, as defined by flanges 12, in order that pan A can be telescoped or snapped 25 into pan B in the manner indicated in Figs. 2 and 3. Preferably a sheet of suitable insulating material C is disposed in proper alignment between pan A and B during the panel assembly in order to incorporate said insulating material within the assembled panel unit. It is evident that when pan A is telescoped into pan B corner slits 7 permit flanges 8 of pan A to be sprung inwardly, whereas the corner slits of pan B permit flanges 12 to be sprung outwardly during the assembly 30 operation. The natural elasticity of the material used, such as metal, returns the flanges 8 and 12 to their original position wherein it is seen that edges 16 of inner locking strips 15 snap into abutting and locking engagement with complementary edges 14 of outer locking strips 13 of pan A.

In the panel construction hereinabove described it is seen that flanges 12 of pan B form rounded and finished top, bottom and side edges 45 of an assembled panel unit.

Although the telescopic locking engagement between pans A and B, as above set forth, is sufficient to maintain the assembled panel unit together for all practical operational purposes, 50 we prefer to weld the open seams formed by corner slits 7 in order to present a flat smooth and continuous corner surface which may be painted, enameled, or attractively finished by other suitable means. Similarly, open seams 20 55 which are formed where the edges of flanges 12

of pan B join the flat section 9 of pan A may be welded, as indicated at 17, in order to present a more finished appearance.

Figs. 4 and 5 illustrate a preferred modification of the panel construction which said particular embodiment is especially suited as a partitioning wall between adjoining stalls or booths and wherein said panel is disposed between and supported at its opposite ends by vertical studs, such as indicated at 21. In this type of construction it is necessary only to provide the tops and bottoms of the two telescopically coacting pans A' and B' with outwardly extending marginal flanges 22 and 23, respectively. It will suffice to relate merely that flanges 22 and 23 are formed substantially in the same manner as are flanges 8 and 12 of pans A and B, and are arranged and constructed to telescopically engage and lock with one another substantially in the same manner as set forth with respect to the description of the manner of assembly of pans A and B. The vertical edges 24 and 25 of pans A' and B' which abut directly against studs 21 are not flanged but may be directly welded to the studs, such as indicated generally at points 18 in Fig. 5. A suitable sheet of insulating material, as indicated generally at C', may be disposed between telescopically coacting pans A' and B' in a manner substantially as was described with relation to the insertion and assembly of insulating sheet C within pans A and B.

Although we have described our invention in some specific detail for purposes of illustration and by way of example, it is understood that certain changes and modifications may be made without departing from the spirit of the invention or the scope of the appended claims.

We claim:

1. In a panel construction a first pan comprising a flat section and marginal flanges extending outwardly from and in a plane substantially normal to said flat section, said marginal flanges having their edges folded outwardly and doubled back over themselves to substantially half-way points of said flanges to form outer locking strips, a second pan comprising a flat section and having marginal flanges extending outwardly from and in a plane substantially normal to said flat section, said marginal flanges of said second pan having their edges folded inwardly and doubled back over themselves to substantially half-way points of said flanges to form inner locking strips complementary to said outer locking strips of said first pan, the marginal flanges of said first

pan extending outwardly from the flat surface thereof a distance substantially equal to the distance that the marginal flanges of said second pan extend outwardly from the flat surface of said second pan said marginal flanges and said outer locking strips of said first pan telescoped substantially wholly within the marginal flanges and complementary inner locking strips of said second pan with the edges of the locking strips in abutment, whereby said pans lock together to form an assembled panel unit.

2. In a panel construction a first pan comprising a flat section and marginal flanges extending outwardly from and in a plane substantially normal to said flat section, said marginal flanges being curvilinear in cross section, said marginal flanges having their edges folded outwardly and doubled back over themselves to substantially half-way points of said flanges to form outer locking strips, a second pan comprising a flat section and having marginal flanges extending outwardly from and in a plane substantially normal to said flat section, said marginal flanges of said second pan being curvilinear in cross-section, said marginal flanges of said second pan having their edges folded inwardly and doubled back over themselves to substantially half-way points of said flanges to form inner locking strips complementary to said outer locking strips of said first pan, the marginal flanges of said first pan extending outwardly from the flat surface thereof a distance substantially equal to the distance that the marginal flanges of said second pan extend outwardly from the flat surface of said second pan said marginal flanges and said outer locking strips of said first pan telescoped substantially wholly within the marginal flanges and complementary inner locking strips of said second pan with the edges of the locking strips in abutment, whereby said pans lock together to form an assembled panel unit.
